Application February 4, 1938, Serial No. 74,876

To all whom it may concern:

Be it known that I, Eugen Prestinari, a citizen

invented a new, original, and ornamental Design
for a Watch Bracelet, of which the following is a

panying drawing, forming a part thereof.

In the drawing,

Figure 1 is a plan view of a portion of a watch
bracelet showing my new design; and

Figure 2 is a side elevational view of the brace-
let shown in Figure 1.

The drawing discloses one-half of the watch
bracelet, the other half being a duplication of
that shown.

I claim:

The ornamental design for a watch bracelet as
shown and described.
